UNITED STATES PATENT OFFICE.

LEWIS L. PHILLIPS, OF MINEOLA, NEW YORK.

MEANS FOR PREVENTING FIRE IN MOVING-FICTION APPARATUS.

1,198,758.

Specification of Letters Patent. Patented Sept. 19, 1916.

Application filed September 4, 1915. Serial No. 48,953.

To all whom it may concern:

Be it known that I, LEWIS L. PHILLIPS, a citizen of the United States, and residing at Mineola, Long Island, in the county of 5 Nassau and State of New York, have invented certain new and useful Improvements in Means for Preventing Fire in Moving-Picture Apparatus, of which the following is a specification, such as will enable those 10 skilled in the art to which it appertains to make and use the same.

This invention relates to means for preventing fire in moving picture apparatus and particularly fires that are started by the ignition of the film occasioned by the heat of the rays of the light from the projector when the film for any reason is broken, and the object of the invention is to provide improved means for the prevention of such 15 fires, said means being automatic in operation, and with this and other objects in view the invention consists in means or apparatus of the class specified, constructed and operated as hereinafter described and claimed.

20 The invention is fully disclosed in the following specification, of which the accompanying drawing forms a part, in which the separate parts of my improvement are designated by suitable reference characters in 25 each of the views, and in which:—

Figure 1 is a sectional view of a part of a moving picture apparatus involving my invention; Fig. 2 a view at right angles to that of Fig. 1 and showing only details of 30 the construction and on an enlarged scale; and, Fig. 3 a section on the line 3—3 of Fig. 35 1 on an enlarged scale.

In the accompanying drawing, reference 40 being made to Fig. 1, particularly, I have shown a part of a moving picture apparatus involving a top magazine *a* and a bottom magazine *b* in which the film reels *c* and *d* are mounted, and the magazines *a* and *b* are connected, as shown, by a vertical casing *e* 45 involving front and back plates *e*² and *e*³ having light apertures *e*⁴ and *e*⁵.

50 Adjacent to the back plate *e*³ and at the front thereof and adjacent to the top thereof is mounted the usual film roller *f* below which and below the light aperture *e*⁴ is another film roller *f*², below which is a third film roller *f*³, all this being of the usual construction, and the film *g* which is wound on one of the reels *c*—*d* and adapted to be 55 wound onto the other is passed through an aperture *a*² in the bottom of the top maga-

zine *a* backwardly and around the roller *f* down to and around the roller *f*², after which a loop of slack *g*² is formed in said film, after which said film is passed backwardly 60 and around the roller *f*³ and down into the magazine *b* where it is connected with the reel *d*.

Pivoted to the top of the magazine *b* is a 65 gate *h* adapted to swing horizontally, and the pivotal point of which is shown at *h*² in Fig. 3, and all this construction is also old and well known and the gate *h* may be of any desired form and may be pivoted or hinged in any desired manner.

I have also shown at *i* the light discharge 70 tube of an ordinary projector and, in the practice of my invention, I secure to the top of the bottom magazine *b* a telescopic standard *j*, comprising a bottom part *j*² pivoted to the top *b*² of the bottom magazine at *b*³, and a vertically movable top part *j*³ having a forwardly directed arm *j*⁴, and the top part *j*³ of the standard *j* may be adjustably secured to the bottom part *j*² by a set 75 screw *j*⁵.

Placed on the top of the magazine *b* back of the back plate *e*³ of the casing *e* is a plate *k* provided at its ends with raised ears *k*² in which is mounted a rock shaft *m* provided at one end with an arm *m*² and at the opposite end with a crank *m*³ on which is mounted a roller *m*⁴, and the back plate *e*³ of the casing *e* is provided at the bottom thereof with an aperture *e*⁶ through which 80 the crank *m*³ operates.

The outer end of the plate *k* is provided with an arc-shaped stop plate *k*⁵ in connection with which the arm *m*² operates to limit the rotation of the shaft *m* and the crank *m*³ 85 with its roller *m*⁴ operates within the gate *h* as well as through the rear casing plate *e*³.

Mounted in the top of the standard *j* below the arm *j*⁴ is a horizontal rod *n* on which is secured a plate *n*² which is preferably 90 round as indicated in dotted lines in Fig. 2, and the rod *n* is provided at one end with an arm *n*³ which extends at right angles thereto and a cord or wire *o* is connected with the arm *n*³ and with the arm *m*².

After the film *g* has been passed around or in connection with the rollers *f*, *f*² and *f*³, as hereinbefore described, it is passed back of the roller *m*⁴, as shown in Fig. 1 and connected with the reel *d*.

The full line position of the various parts, as shown in Fig. 1, is the position said parts

occupy when the apparatus is in use, and it is a well-known fact that in the use of apparatus of this class the film, if broken is usually broken below the roller f^2 , and the 5 hot rays of light from the projector tube i^2 striking the film ignites it and thus starts a fire due to the fact that said film is usually made out of highly combustible material. With my improvement, however, if the film 10 should be broken, as above described, the crank m^3 and its roller m^4 will at once drop into the position shown in dotted lines in Fig. 1, and the plate n^2 which operates as a shield would also drop into the position 15 shown in dotted lines in Fig. 1, and the rays of light will be cut off and the film g would not be ignited. In this operation, the arm n^3 of the rod n also is thrown into the position shown in dotted lines in Fig. 1, as 20 is the arm m^2 of the shaft m , and it will be observed that the arm m^2 is outside of the casing e , while the crank arm m^3 in its normal position is inside of said casing.

It will be understood that my invention 25 is not limited to the exact details of the construction herein shown and described. The main idea being the provision of the shield device which in the event of the breaking of the film is automatically thrown into 30 position to cut off the rays of light from the projector, and various changes in and modifications of the construction herein described may be made, within the scope of the appended claims, without departing from the 35 spirit of my invention or sacrificing its advantages.

Having fully described my invention, what I claim as new and desire to secure by Letters Patent, is:—

40 1. In a moving picture apparatus, the combination with a shield located between the projector and the film, of a roller against which the film bears, and mechanical means permanently connecting said roller with said 45 shield, whereby the film, through said roller and connecting means, normally serves to support the shield in inoperative position and the breaking of the film will release said

50 roller and permit the shield to move into operative position.

2. In a moving picture apparatus, the combination with a pivoted support carrying a shield which is located between the projector and the film, of a roller against which the film bears, and mechanical means 55 permanently connecting said roller with said shield support whereby the film, through said roller and connecting means, normally serves to support the shield in inoperative position and the breaking of the film will 60 release said roller and permit the shield to drop into operative position.

3. In a moving picture apparatus, the combination with a pivoted support carrying a shield which is located between the 65 projector and the film, of a rock shaft provided with a roller against which the film bears, and mechanical means permanently connecting said rock shaft and said support, whereby the film through said roller, rock 70 shaft and connecting means, normally serves to support the shield in inoperative position and the breaking of the film will release said roller and permit the shield to move 75 into operative position.

4. In a moving picture apparatus, the combination with a standard, of a rod pivotally mounted therein and provided with an arm, a shield secured to said rod and located between the projector and the film, 80 a rock shaft provided with a roller against which the film bears, an arm provided on said rock shaft, and means connecting the rock shaft arm and rod arm, whereby said film normally serves to support said shield 85 in inoperative position and the breaking of the film will release said shaft to permit said shield to drop into operative position.

In testimony that I claim the foregoing as my invention, I have signed my name in 90 presence of the subscribing witnesses this 3rd day of September, 1915.

LEWIS L. PHILLIPS.
